(57) **CLAIM**

The ornamental design for an oar carrier, as shown and described.

DESCRIPTION

This application is related to co-pending U.S. patent application Ser. No. 14/253,498, filed on Apr. 15, 2014, the disclosures of which are included by reference herein in their entirety.

FIG. 1 is a front perspective view of an oar carrier showing our new design;

FIG. 2 is a front elevation view thereof, the rear elevation view being a mirror image thereof;

FIG. 3 is a left side elevation view thereof;

FIG. 4 is a right side elevation view thereof;

FIG. 5 is a top view thereof;

FIG. 6 is a bottom view thereof; and,

FIG. 7 is a front perspective view of the new design in a typical environment, the rear perspective view being a mirror image thereof.

The broken lines shown in the figures are included for the purposes of illustrating environment and form no part of the claimed design.
